UNITED STATES PATENT OFFICE

2,513,578

SAFETY SHUTOFF CONTROL SYSTEM FOR
GAS BURNERSRussell Matthews, Wauwatosa, Wis., assignor to
Milwaukee Gas Specialty Company, Milwaukee,
Wis., a corporation of Wisconsin

Application April 15, 1947, Serial No. 741,439

14 Claims. (Cl. 158—117.1)

1

This invention relates, in general, to ignition systems and has particular relation to an improved single point ignition system for fuel burners.

While the particular embodiment of the invention which I shall describe hereinafter in connection with the drawings is a single point ignition system adapted for use with domestic gas ranges, it is to be understood that the invention is not limited to such use but may be employed for all similar purposes, for example, in connection with various commercial forms of apparatus having a baking oven burner, broiler oven burner or other burner remotely located relative to the pilot burner.

In the usual domestic gas range, the pilot burner is in the form of a single constantly burning pilot located in juxtaposition to the top burners at the upper part of the range, and the baking oven, broiler or like burners are located in the lower part of the range. Although the top burners are usually provided with a constantly burning pilot burner for lighting the same, at the present time a match is usually employed for lighting the baking oven, broiler, or like burners. The stooping and hazards of lighting an oven burner or the like with a match are well known in the art.

In the copending application of Ernst Witzel, Serial No. 738,412, filed March 31, 1947, and owned by the owner of the present application there is provided an improved system of flash tubes and intermediate pilot means for assuring ignition of a pilot in juxtaposition to the oven or like burner from a constantly burning top pilot; also an improved single point ignition system wherein means is provided for extinguishing the intermediate pilot means and establishing a flow of fuel to the oven or like burner after a time delay following ignition of the burner pilot, and an improved thermoelectric control device and other instrumentalities for accomplishing the new and advantageous results therein set forth.

In the copending application of Ernst Witzel, Serial No. 744,905, filed April 30, 1947, and owned by the owner of the present application there is provided a simple, improved and effective single point ignition system which will provide all of the advantageous results obtained with

2

the systems disclosed and claimed in the above identified copending application and in which the gas cock in the fuel supply line is the only item requiring actuation manually to secure the desired single point ignition.

One of the main objects of the present invention is to provide a simple, improved and effective single point ignition system, in general, of the character to which the last mentioned copending application is directed, and in which the main valve will close very quickly when the thermoelectric generator is not heated by its pilot.

Another object of the invention is to provide an improved form of control in which sufficient power is generated by heating of the thermoelectric generator by its pilot to move the main valve to open position, whereas upon opening of this valve the holding power of the electromagnet is reduced to an amount sufficient to hold the valve open but insufficient to move it to open position.

Another object of the invention is to provide an improved arrangement of electric components comprising a resistor connected with the thermoelectric circuit; a switch responsive to the pressure in the fuel supply line, when closed, connecting the thermoelectric generator with the electromagnet around the resistor and the thermoelectric generator being connected with the electromagnet in series with the resistor when the switch is open.

Another object of the invention is to provide an improved form of thermoelectric control device for accomplishing the advantageous results set forth, and, more particularly, an improved form of combined thermoelectric valve and switch in which the pressure for moving the switch controlling diaphragm to position closing the switch is neutralized for movement of the switch to open position upon opening of the main valve.

Another object of the invention is to provide a single point ignition system and instrumentalities therein, as will hereinafter appear, having various features of novelty and advantages, and which are particularly characterized by their simplicity in construction, their economy in manufacture and installation, and their effectiveness in use.

Further objects and advantages of the invention will appear from the following detailed description, taken in connection with the accompanying drawings which illustrate the manner of constructing and operating an illustrative embodiment of the invention.

In the drawings:

Figures 1 and 1A are parts of a diagrammatic view which, when placed with Figure 1A to the right of Figure 1 and the line B—B of Figure 1A on the line A—A of Figure 1, form a complete diagrammatic view of one form of single point ignition system embodying the present invention.

Referring now to the drawings, the burner 1 is the baking oven, broiler or other remote burner. It is usually located in the lower part of the range or other appliance.

The pilot 2 is the constantly burning pilot. It may be, for example, the top pilot for the top burners of a gas range or other constantly burning pilot. The pilot 2 is usually located in the upper part of the appliance.

A fuel supply pipe 3 leads to the burner 1 for the delivery of gaseous or other fuel thereto, for example, through a mixing chamber 4 to which air is admitted through adjustable air inlets (not shown), as well understood in the art. The flow of gas through the pipe 3 is controlled by a thermoelectric control valve 5 and by a gas cock 6 connected into the pipe 3 anterior of the valve 5.

The oven or like burner 1 is provided with an oven or like pilot 7 for igniting it. A flash tube 8 has a laterally turned upper end opening directly to the constantly burning pilot 2. This tube extends downwardly and opens at its lower end to an intermediate pilot 9. The intermediate pilot 9 is spaced laterally from the oven pilot 7, and the tube 8 has at its lower end a generally horizontally extending branch 8' which opens at its outer end directly over the flame position 10 of the oven pilot 7.

The thermoelectric control device 5 comprises a valve body formed of top and bottom valve body parts 15 and 16 clamped together by screws (not shown) with a diaphragm 18 therebetween. The valve body part 15 has an inlet 19 and an outlet 20. Contiguous sections of the fuel supply pipe 3 are connected to the inlet 19 and outlet 20, for example, by screwing them into the inlet and outlet, which are shown as internally threaded. Internally the valve body part 15 has a generally L-shaped outlet chamber 21 having a longitudinally extending part in open communication with the outlet 20, and a transversely extending portion defined by a cylindrical wall 22. An inlet chamber 23, in open communication with the inlet 19, terminates at its inner end in a generally annular-shaped portion which embraces the cylindrical wall 22.

The wall 22 terminates in an annular valve seat 24. An armature 25, of disc-like form, has a yielding or other suitable valve or valve facing 26 adapted to seat against the seat 24 to shut off the flow of gas from inlet 19 to outlet 20 through chamber 21. A hood 27 is clamped to the valve body part 15 by a union nut 28, and preferably with a hood gasket 29 therebetween.

In the illustrated embodiment of the invention, the means for operating the valve 26, and, more particularly, the means for opening this valve, is in the form of an electromagnet comprising a magnet frame or coil spool 30 and a coil 31. One side of the coil 31 is connected by a

lead 32 to one of the thermocouple elements 33 of a thermocouple 34 or other suitable thermoelectric generator (such as a thermopile). The other element 35 of the thermocouple 34 is connected by a lead 36 to one contact 37 of a tilting mercury switch 38 within the valve body part 16. The other and adjacent contact 39 of the switch 38 is connected by a lead 40 to the other side of the coil 31.

A resistance or resistor 42 is connected in parallel with the contacts 37, 39, for example by connecting one side of the resistor to the conductor 36, at 43, and the other side of the resistor to the conductor 40, at 44. The resistor 42 is so proportioned that the electromagnet cannot open the valve 26 by lifting the armature 25 by the heat of the pilot 7 on thermocouple 34 when the mercury switch is open at contacts 37, 39 and the thermoelectric circuit is completed only through the resistor 42. Once moved to open position however, the valve 26 will be retained open, with the switch contacts open at 37, 39. When switch 38 is closed at contacts 37, 39 the thermoelectric generator 34 is connected with the electromagnet around resistor 42, and at that time the power generated by the heat of the pilot on the thermoelectric generator is sufficient to move the valve 26 to open position.

The thermocouple 34 and lead connections therefor may be of the general character disclosed and claimed in Oscar J. Leins Patent No. 2,126,564, granted August 9, 1938, or it may be of any other suitable character, or in the form of a thermopile or other thermoelectric generator. The thermoelectric generator has one or more hot junctions, for example the hot junction 46, which is placed in position to be heated by the flame 47 of the burner pilot 7.

In the illustrated embodiment of the invention, the electromagnet has a flux shell 50 and a spacer ring 51. The lower end of the coil spool 30 has an axial recess, and disposed in this recess and interposed between spool 30 and armature 25 is a coiled spring 52 which operates to move armature 25 to retracted position and to seat the valve 26 on valve seat 24 when the electromagnet is deenergized. Energization of the electromagnet by heating of the hot junction of the thermocouple 34 is sufficient to lift valve 26 to open position against the action of spring 52 when, as already pointed out, the switch 38 is closed at the contacts 37, 39 so that the thermoelectric circuit is completed around the resistor 42. A hood spring 53, interposed between the top of the spool 30 and hood 27, seats the shell 50 in the valve body part 15 at 54. In commercial practice, one of the thermocouple elements, for example the outer tubular thermocouple element 33, may be grounded, and one side of the coil 31 may be grounded to the valve body.

The bottom of the valve body part 15 has a recess 60 spaced inwardly from its periphery. Disposed in this recess and above diaphragm 18 is a cover plate 61 clamped to valve body part 15 by screws (not shown) with a diaphragm 62 therebetween. A port 63 opens from inlet chamber 23 into chamber 64 above diaphragm 62. Another port 65 opens from inlet chamber 23 into chamber 66 above diaphragm 18.

The valve body part 15 has a pilot outlet passage 67 for supplying fuel to the intermediate pilot 9 through a pipe 68. Fuel is adapted to be delivered from the diaphragm chamber 64 to the passage 67 through a passage 70, the lower end of which is surrounded by an annular valve seat

71. A valve or valve facing member 72 is adapted to seat against seat 71 to shut off the supply of fuel to the intermediate pilot 9. The burner pilot 7 is supplied with fuel by a pipe 73 connected at 74, for example, to the fuel supply pipe 3 between gas cock 6 and the thermoelectric control device 5. The constantly burning pilot 2 is supplied with fuel by a pipe 75 connected at 76, for example, to the fuel supply pipe 3 anterior of the gas cock 6.

The diaphragm 62 may have diaphragm plates, and interposed between the bottom of this diaphragm and cover plate 61 is a spring 79. A port 80 opens from the outlet chamber 21 and through port 81 into chamber 82 beneath diaphragm 62. Passage 83 opens from outlet chamber 21 into chamber 84 beneath diaphragm 18.

The mercury bulb 38 of the mercury switch is carried by a bulb holder 85 pivoted at 86. The bulb holder has pins 88 which are engaged by the notched lower ends of the depending legs of a diaphragm bracket 89. The diaphragm 18 may have diaphragm plates, and bracket 89 is secured to the diaphragm at the axis thereof, for example, by a rivet (not shown). A spring arm 92 is notched at one end at 93 for engagement of pins 88 therein. The other end of arm 92 is notched at 94 for engagement with a pin 95. The pin 95 is carried by a spring arm bracket 96 secured to the bottom of the valve body part 16. A coiled spring 98 is interposed between the arm 92 and the base of bracket 96.

The operation of the system shown in the drawings is as follows:

When gas cock 6 is opened, gas is admitted to the tops of diaphragms 62 and 18 by means of ports 63 and 65. Valve 72 will open against the pressure of spring 79, and gas will flow to the intermediate pilot 9 through passage 67 and pipe or tube 68. Opening of gas cock 6 also admits gas to burner pilot 7 through pipe or tube 73. The gas from the intermediate and oven pilots rises in tube 8 which is always relatively cool to permit this action. As it reaches the flame of constantly burning pilot 2, the gas is ignited and then recedes or flashes back to light the intermediate and burner pilots 9 and 7. The turning of the upper end of the flash tube laterally toward pilot 2 reduces the possibility of extinguishing this pilot by flash-back action in tube 8.

The pressure exerted on diaphragm 18 through port 65, upon opening of gas cock 6, moves the diaphragm 18 downwardly to its lowest position. This tips mercury bulb 38 in a counterclockwise direction about its pivot 86 as viewed in Figure 1, sufficiently to make contact at 37, 39, thus completing the circuit between thermoelectric generator 34 and coil 31 around the resistor 42. When, with the switch 38 closed at contacts 37, 39, the electromagnet is energized sufficiently by the heat of the pilot flame 47 on thermoelectric generator 34 to lift valve 26 to open position, gas is admitted to the oven burner 1 through outlet 20 and fuel supply pipe 3.

Gas pressure is now exerted on the under side of diaphragm 62 through ports 80 and 81, and also on the under side of diaphragm 18 through passage 83. This neutralizes pressures on opposite sides of diaphragm 62; also on opposite sides of diaphragm 18. As a result, valve 72 closes with the help of spring 79, thereby stopping or shutting off the supply of gas to the intermediate pilot 9, and diaphragm 18 returns to its top position, as viewed in Figure 1, with the

help of spring 98. This breaks the electric circuit at contacts 37, 39, but the resistor 42 will maintain the circuit and hold armature 25 in attracted position and valve 26 open once it has been opened by the electromagnet.

Whenever gas cock 6 is closed, extinguishing pilot 7, the thermoelectric generator 34 is cooled. The loss of energy is sufficient to weaken or reduce the holding power of the electromagnet

10 so that the valve 26 will move to closed position within a relatively short time since, with resistor 42 in the circuit, just enough power was maintained to hold the valve 26 in open position. In the illustrated embodiment of the invention, 15 when thermoelectric generator 34 is not heated by pilot 7, valve 26 will close very fast, for example, in about five seconds instead of about forty seconds with contact made at 37, 39.

As previously pointed out, the electromagnet 20 cannot open the valve 26 with the circuit completed only through resistor 42. Contact must be closed at 37, 39 for this purpose. Once opened, the valve 26 will be retained open by the electromagnet without contact at 37, 39.

If desired, the fuel supply pipe 3 may be provided with a thermostat valve 110 connected, for example, by a tube 111 to a thermostat bulb 112 located where it will be subject to the heat of the oven burner 1. In such case, the thermostat bulb 112 and its connected thermostat valve 110 serve as a limit device for shutting off the flow of fuel to the burner 1 upon the occurrence of predetermined maximum temperatures. The thermostat may, of course, be adjusted to operate at different temperatures, and I contemplate other forms of thermostats and other forms of thermostatic controls than the one shown in the drawings, which is for purposes of illustration.

40 The present invention contemplates many variations in the form and details of the single point ignition system shown in the drawings, and many variations in the form and details of the electric components shown and described. 45 The embodiment of the invention shown in the drawings is, therefore, for illustrative purposes only, and it is to be expressly understood that the drawings and the accompanying specification are not to be construed as a definition of the 50 limits or scope of the invention, reference being had to the appended claims for that purpose.

I claim:

1. In combination, a thermo-electrically operated valve for controlling the supply of fuel for 55 a burner, an electromagnet for said valve, a thermoelectric generator adapted to be heated by a pilot flame and connected in circuit with said electromagnet for energizing said electromagnet to operate said valve to open position, resistor 60 means for increasing the resistance of the circuit between the thermoelectric generator and the electromagnet, and means responsive to the opening of said valve for completing the circuit between said thermoelectric generator and said 65 electromagnet through said resistor means to energize said electromagnet sufficiently to hold said valve open but insufficiently to open said valve.

2. In combination, a thermo-electrically operated valve for controlling the supply of fuel for a burner, an electromagnet for said valve, a thermoelectric generator adapted to be heated by a pilot flame and connected in circuit with said electromagnet for energizing said electromagnet to operate said valve to open position, means

under control of the pressure of the fuel and operating upon opening of said valve to reduce the energy of said electromagnet to an amount just sufficient to hold said valve in open position but insufficient to open the valve.

3. In combination, a thermoelectrically operated valve for controlling the supply of fuel for a burner, an electromagnet for said valve, a thermoelectric generator adapted to be heated by a pilot flame and connected in circuit with said electromagnet for energizing said electromagnet to operate said valve to open position, resistor means for increasing the resistance of the circuit between the thermoelectric generator and the electromagnet, and means responsive to the opening of said valve for completing the circuit between said thermoelectric generator and said electromagnet through said resistor means to energize said electromagnet sufficiently to hold said valve open but insufficiently to open said valve, said last means being responsive to the pressure of fuel admitted to said valve for completing the circuit between said thermoelectric generator and said electromagnet around said resistor means prior to opening said valve to energize said electromagnet sufficiently to open the valve.

4. In apparatus of the class described, in combination, a thermoelectric generator, a circuit connected to said thermoelectric generator and including an electromagnet, a fluid flow controlling member having a first position shutting off fluid flow and adapted to be moved by energization of said electromagnet by said thermoelectric generator to a second position permitting fluid flow, means rendered operative upon movement of said flow controlling member to said second position for reducing the energy of said electromagnet in such amount that the electromagnet is capable of holding said flow controlling member in said second position but is incapable of moving said member to such position, said last means comprising a switch in said circuit, and a resistor in parallel with said switch, said switch being actuated from one position to another position by the pressure of the fluid controlled by said fluid flow controlling member.

5. In apparatus of the class described, in combination, a constantly burning pilot burner, a burner remote from said constantly burning pilot burner, a burner-igniting pilot burner for igniting said burner, intermediate pilot burner means for assuring ignition of said burner-igniting pilot burner from said constantly burning pilot burner, a fuel supply line for supplying fuel to said burner and said pilot burners, a gas cock in said fuel supply line, a control valve in said fuel supply line on the outlet side of said gas cock, means for actuating said control valve to open position and for holding it open, and means rendered operable by the opening of said gas cock to establish a flow of fuel to said intermediate pilot burner means and to said burner and to extinguish said intermediate burner pilot means and reduce the energy of the means for holding said control valve in open position upon establishment of a flow of fuel to said burner.

6. Apparatus according to claim 5 wherein the means for actuating the control valve to open position and holding it open comprises an electromagnet connected in circuit with a thermoelectric generator and wherein the means for reducing the power of said electromagnet comprises a switch in said circuit and a resistor connected in parallel with said switch.

7. In a device of the class described, in combination, a main burner, an intermediate pilot burner, a valve body having an inlet, an outlet for supplying fuel to said main burner, a main valve member, and an outlet for supplying fuel to said intermediate pilot burner, a pair of diaphragms responsive to the pressure on the inlet side of said main valve member, a second valve member responsive to one of said diaphragms for opening the outlet for the intermediate pilot burner, and means responsive to the movement of said other diaphragm for opening and holding open said main valve member for the supply of fuel to the main burner and for reducing the energy of said holding means upon opening of said main valve member.

8. Apparatus according to claim 7 wherein the means for opening and holding open said main valve comprises an electromagnet connected in circuit with a thermoelectric generator and wherein the means for reducing the energy of the holding means comprises a switch in said circuit and a resistor connected in parallel with said switch.

9. Apparatus according to claim 7 wherein the diaphragms for the pilot and main valves are responsive to the pressure on the outlet side of said main valve upon opening of said valve.

10. In a device of the class described, in combination, a main burner, an intermediate pilot burner, a valve body having an inlet, an outlet for supplying fuel to said main burner, a main valve member, and an outlet for supplying fuel to said intermediate pilot burner, an electromagnet connected in circuit with a thermoelectric generator for opening said main valve member and holding it open, a pair of diaphragms responsive to pressure on the inlet side of said main valve member, a second valve member responsive to movement of one of said diaphragms for opening the outlet for the intermediate pilot burner, a resistor, and means responsive to the movement of the other diaphragm for placing said resistor in circuit in series with said electromagnet and thermoelectric generator upon opening of said main valve member.

11. Apparatus according to claim 10 wherein said last means comprises a switch connected in parallel with the resistor and actuated by said other diaphragm.

12. Apparatus according to claim 10 wherein said last means comprises a switch connected in parallel with the resistor and actuated by said other diaphragm, and wherein both said diaphragms are responsive to the pressure on the outlet side of said main valve member upon opening of said main valve member for movement of said second pilot burner valve to closed position and said switch to open position.

13. In apparatus of the class described, in combination, a constantly burning pilot burner, a burner remote from said constantly burning pilot burner, a burner-igniting pilot burner for igniting said burner, intermediate pilot burner means for assuring ignition of said burner-igniting pilot burner from said constantly burning pilot burner, a fuel supply line for supplying fuel to said burner and said pilot burners, shut-off means in said fuel supply line, a control valve in said fuel supply line on the outlet side of said shut-off means, means for actuating said control valve to open position and for holding it open, and means rendered operable by the opening of said shut-off means to establish a flow of fuel to said intermediate pilot burner means and to said

burner and to extinguish said intermediate pilot burner means and reduce the power of the means for holding said control means in open position upon establishment of a flow of fuel to said burner.

14. In combination, a thermoelectrically operated valve for controlling the supply of fuel for a burner, an electromagnet for said valve, a thermoelectric generator adapted to be heated by a pilot flame and connected in circuit with said electromagnet for energizing said electromagnet to operate said valve to open position, resistor means for increasing the resistance of the circuit between the thermoelectric generator and the electromagnet, and means responsive to the pressure of fuel admitted to said valve for completing the circuit between said thermoelectric generator and said electromagnet around said resistor means prior to opening said valve to energize said electromagnet sufficiently to open the valve.
